UNITED STATES PATENT OFFICE.

M. H. MERRIAM AND E. L. NORTON, OF CHARLESTOWN, MASSACHUSETTS.

IMPROVED SORTING-MACHINE.

Specification forming part of Letters Patent No. 55,331, dated June 5, 1866.

To all whom it may concern:

Be it known that we, M. H. MERRIAM and E. L. NORTON, both of Charlestown, in the county of Middlesex and State of Massachusetts, have invented an Improved Machine for Sorting Shoe-Binding Strips; and we do hereby declare that the following, taken in connection with the drawings which accompany and form part of this specification, is a description of our invention sufficient to enable those skilled in the art to practice it.

The invention relates to the manufacture of shoe-binding, and particularly to that one of the series of operations converting the skin into shoe-binding ribbon in which the strips of leather cut from the skin are sorted into parcels according to thickness.

The invention consists in the combination, with contact-surfaces between which each strip is placed, of an index and index mechanism, operated by the movement of one of the contact-surfaces and indicating, through numbers, letters, or otherwise, the thickness of each strip passed between the surfaces; also, the employment of feed-rollers for the contact-surfaces, one being movable with respect to the other, and the movable roll being connected with and operating the indicating mechanism; also, overhanging the rollers so as to bring them into convenient position with respect to the table over which the strips are introduced to the rolls; also, making the housings or frame in which the contact rolls or surfaces are mounted movable, so that the index or dial-pointer may be adjusted to the 0 or starting-point upon the dial.

A machine embodying the invention is represented in the drawings—

Figure 1 showing a front elevation of it; Fig. 2, a horizontal section taken in the line *a a*, of the axis of the index-pointer; Fig. 3, a vertical transverse section taken on the line *b b*, between the rollers and index-stand, and looking toward the rollers.

a denotes a bed or platform having erected upon it a standard, *b*, for the support of housings for the shafts of two rollers, *c d*. *e* is a table so placed with respect to the rollers that the strip of leather can be guided over its surface by hand until the rolls bite upon it, the lower roll being turned by any suitable power to cause the rolls to feed the material between

them. The shaft of the lower roll rotates in stationary bearings, but the upper roll is journaled in a swing-frame, *f*, so that it may rise and fall, with respect to the lower roll, according to the thickness of the material being passed between them, the upper roll being kept to the surface of the material by gravity or by suitable springs. From this frame *f* a lever, *g*, extends, as seen in Fig. 1, the outer end of this lever being jointed by a connecting-rod, *h*, to a crank on a gear-wheel, *i*, this wheel meshing into and driving an index-wheel, *k*, carrying a pointer, *l*, the extent of vertical motion of the connecting-rod turning the wheel *n*, and through it the index-wheel *k*, sufficiently to carry the pointer nearly round the dial or index-face *m*. This face has indicating-marks to designate through the movement of the pointer the thickness of the material run through the rolls.

The frame which carries the rolls is made capable of vertical movement on the standard *b*, this movement being produced by an adjusting-screw, *n'*, and permitting the lever *g* to be elevated or depressed when the rolls are in contact, to bring the index-pointer opposite to the 0, or starting-point on the dial-face. For convenience in entering the strips between the contact-surfaces the rolls are overhung, as seen in the drawings.

When a strip is fed between the rolls the pointer will be carried round till it reaches the mark corresponding with the thickness of the material, and will vibrate opposite such mark, which will indicate to the attendant the general or average thickness of each strip, and enable her to parcel out the several strips according to the thickness of each, the strips not varying much in thickness along the length of each, but having such variation with respect to each other as to render it necessary to grade them in parcels according to the thickness of each.

It will be obvious that a stationary edge or surface may be employed instead of the lower roll, and a vertically-moving edge instead of the upper one, the strip being fed through by hand or by only one roll; but the arrangement shown is considered preferable; or the strip may be placed upon a straight bed-piece, and a movable straight-edge brought down upon the strip, indicating at once through the index

mechanism the general or average thickness of the strip.

We claim—

1. The combination, with contact-surfaces between which the strip of leather is placed or passed, of an index mechanism operated by the movement of the movable contact-surface, substantially as set forth.

2. The employment of the feed-rollers, in combination with the index mechanism, one of the rollers operating the index by its movement, substantially as set forth.

3. Overhanging the rollers which feed the material and operate the index mechanism.

4. Making the rollers or the roller-frame adjustable as to height, so as to set the index-pointer to the starting-point of the dial.

In witness whereof we have hereunto set our hands this 24th day of November, A. D. 1865.

M. H. MERRIAM.
E. L. NORTON.
